COMBINED CAMERA SUPPORT AND FLOOD-LIGHT LAMP HOLDER

Abraham Secofsky and Murray A. Meisel, Brooklyn, and Alexander Zalman, Kew Gardens Hills, N. Y.

Application October 22, 1951, Serial No. 17,062

Term of patent 14 years

(Cl. D61—1)

To all whom it may concern:

Be it known that we, Abraham Secofsky, Murray A. Meisel, and Alexander Zalman, all citizens of the United States, and residing respectively at Brooklyn, in the county of Kings and State of New York, at Brooklyn, in the county of Kings and State of New York, and at Kew Gardens Hills, in the county of Queens and State of New York, have invented a new, original, and ornamental Design for a Combined Camera Support and Floodlight Lamp Holder, of which the following is a specification, reference being had to the accompanying drawing, forming a part thereof.

Fig. 1 is a fragmentary perspective view of a combined camera support and floodlight lamp holder, showing our new design.

Fig. 2 is a top plan view thereof.

Fig. 3 is a rear elevational view thereof.

Fig. 4 is a front elevational view, but showing the arms in collapsed condition.

Fig. 5 is a side elevational view of Fig. 4.

The essential features of the design reside in the portions shown in solid lines.

We claim:

The ornamental design for a combined camera support and floodlight lamp holder, substantially as shown and described.

ABRAHAM SECOFSKY.

MURRAY A. MEISEL.

ALEXANDER ZALMAN.
